[57] CLAIM

The ornamental design for an eyewear lens pair, as shown and described.

DESCRIPTION

FIG. 1 is a front, perspective view of an eyewear lens pair showing my new design;

FIG. 2 is a front, elevational view thereof;

FIG. 3 is a rear, elevational view thereof;

FIG. 4 is a side, elevational view thereof;

FIG. 5 is a top, plan view thereof;

FIG. 6 is a bottom, plan view thereof;

FIG. 7 is a front, perspective view of the left lens of FIG. 1;

FIG. 8 is a front, elevational view of FIG. 7;

FIG. 9 is a front, elevational view of the right lens of FIG. 1;

FIG. 10 is a top, plan view of FIG. 8;

FIG. 11 is a top, plan view of FIG. 9;

FIG. 12 is a side, elevational view of FIG. 8; and,

FIG. 13 is a side, elevational view of FIG. 9.

The broken line showing of the eyewear frame in FIGS. 1-6 is for illustrative purposes only and forms no part of the claimed design.
